UNITED STATES PATENT OFFICE.

JAMES F. VEACO, OF OAKLAND, CALIFORNIA.

CONTINUOUS-TONE PIANO ACTION.

Application filed June 24, 1925. Serial No. 39,184.

This invention relates to a piano action, and an object of the invention is to provide a piano action which is simpler and more efficient than some of the actions now in use.

5 Another object of the invention is to provide means whereby the piano action will produce a continuous tone on any string at the will of the player, without in the slightest degree interfering with the usual operation of the action or the music produced thereby.

10 Another object of the invention is to provide means whereby the continuous tone may be increased or diminished in volume 15 at will.

Another object of the invention is to provide means whereby the slack motion bridle, commonly a small leather strap, will be replaced by a wire arm, which also acts to 20 raise the continuous tone hammer, as well as to cause the reseating of the key hammer.

25 A further object of the invention is to provide means whereby the damper spoon can be adjusted to its proper place from the front of the piano action without removing it therefrom, and without removing the wippen from the piano.

30 Another object of the invention is to provide the key hammer with a steel shank, upon which the hammer is easily rotated and held in any given position by friction, the object being to enable the hammer to be extracted or replaced in a proper position.

35 It will be understood by those skilled in the art, that piano actions must be installed very close together, and must be of a minimum thickness to prevent the required number from becoming too great in length, so that in the present case the change from 40 wooden to steel in certain parts is for the purpose of allowing the necessary strength in the parts, while not increasing the total length of the series of parts that make up a complete piano action.

45 Another object of the invention is to provide means whereby the player will have under his control the operation of the continuous tone action, as well as the speed at which it operates, so that the tone may 50 be varied at will.

Another object of the invention is to provide means whereby the cam, which operates the continuous tone hammers will be

caused to stop in such a position as not to interfere with the usual operation of the 55 piano action, and means is also provided whereby the player can increase or diminish the stroke of the continuous tone hammer to increase or diminish the loudness of the 60 tone at will.

Another object of the invention is to provide means to operate the continuous tone hammers as a separate and complete unit without the standard piano action.

65 Other objects of the invention will appear as the description proceeds.

An embodiment of the invention is shown in the accompanying drawings in which the same reference numeral is applied to the 70 same portion throughout, but I am aware that there may be modifications thereof.

Fig. 1 is a diagrammatic front elevation of a piano, portions thereof being broken away to show the interior mechanism.

Fig. 2 is a view in end elevation of a portion 75 of the piano case showing the operating mechanism for the continuous hammers.

Fig. 3 is a plan view of a portion of the case with the key-board removed and showing the position of the lever for shifting the 80 driving mechanism from one speed to another speed.

Fig. 4 is a view in elevation of the driving mechanism showing the means for shifting the driving gear, looking from the left 85 Fig. 1.

Fig. 5 is a section on line 6—6, Fig. 6, showing a piano action with my invention applied thereto.

Fig. 6 is a front elevation of the piano 90 action as shown in Fig. 5.

Fig. 7 is a section on line 7—7, Fig. 8, showing the continuous tone hammer operating mechanism, slightly modified, as an 95 action complete in itself, independent of the standard piano hammer action.

Fig. 8 is a front elevation of the view shown in Fig. 7.

The numeral 1 represents the case of the piano, which has the usual keys 2, supported in the usual manner over the projecting front 3 of the case.

As is common at the present time, the series of piano actions are supported by four vertical extending frames 4, 5, 6 and 7, 105 which frames are in turn connected to and

supported by the flanged guide rail 8, the main rail 9, and the fixed spring rail 10. A small regulating rail 11, is also carried by a series of projecting arms 12, connected to the rail 9, and the button 13, regulated by the screw eye 14, determines the proper striking effect of the jack 15.

The key 2 is mounted in the piano frame in the usual manner, and when down rests 10 upon the felt strip 15', which extends under the keys.

Each key is provided with a capstan screw 16, which can be adjusted to hold the abstract in any desired position with respect 15 to the rest of the piano movement. The abstract 17 is pivotally connected to the wippen 18, and to a guide link 19, the latter being pivotally connected to a small block 20, secured on the back of the rail 8 by means 20 of a screw 21.

The wippen 18 is pivotally connected to a small block 22, secured on the back of the main rail 9 by means of a screw 23, and it has a hole in its front to receive one end 25 of the damper spoon 24. The damper spoon in this case consists of a rod bent substantially at right angles at 25, and then bent 180° at 26, to allow one end to be inserted in the hole at the front end of the wippen, where it is fixed in position in any desired 30 adjustment by a set screw 27.

The result of the foregoing construction is that the spoon can be adjusted with respect 35 to its contact with the pad 28 on the damper lever 29 by sliding it in or out of the hole in the front end of the wippen, and without otherwise changing its position, without removing it from the action, and without removing the action from the piano.

On the top of the wippen is the jack flange 30, to which the jack 15 is pivoted, and the wippen also carries a spring 31, which bears upon the underside of the horizontal portion of the jack to hold it normally 40 in the position shown in Fig. 5.

The damper lever is pivotally mounted on a small block 32, secured on the top of the main rail 9, by the screw 33, and said lever carries a spring 34, and a rod 35, to which 45 the damper 36 is connected.

When the jack causes the hammer 37 to strike the string 38, the jack comes against the padded jack check rail 39, which rail is supported by several screws 40 extending 50 into the rail 9. Secured by suitable screws to one of the upper vertical surfaces on the rail 9, is a plate 42, which has a projecting post 43, to provide a bearing for each of the pivots 44, which extend through the several hammer butts 45. Each hammer butt is padded in the usual manner, but instead of having the ordinary wooden shank, each hammer butt is provided with a metal shank 46, which is held in place by means of 55 a set screw 47, and at its upper end the shank

extends in the hammer far enough to insure adequate friction to hold the hammer in any given adjustment required of it across the piano, note the different positions of the hammers in Fig. 1.

The wippen also supports a shank 50 on the upper end of each of which shanks there is a padded back check 51, this padded back check strikes the padded head 52 on the shank 53, extending from the hammer butt 75 to hold the hammer in the proper position after it has struck the string.

In order to quickly return the hammer to a position away from the string 38, the spring 54 is provided, which strikes the top 80 of the block 52 when the hammer goes up.

The fixed spring rail 10 is provided with a plurality of pads 55, which support the movable hammer rail 56. The movable hammer rail is carried by a series of arms 57, which are pivotally mounted in the vertical frame members at 58, the object being to provide means for lifting the hammers closer to the strings, in a manner well known in the art, and forming no part of the present invention. 85

In the present instance it will be seen that the movable hammer rail has depending lugs at 57, adjacent each of the vertical frame members to allow it to rest upon the pads 55, at the proper elevation without interfering with the blocks 58, which form the pivotal support for the butts 59 of the continuous tone hammer shanks 60. 90

The continuous tone hammer shanks 60 are bent vertically at their ends nearest the strings and they each carry a butt 61, to which a flexible flat spring hammer shank 62 is secured. This hammer shank has a pad 63 along its entire length, and at its 105 upper end, it is provided with a felt hammer 64.

Extending the entire length of the piano is a rod 65, which is provided with a cam 66, and at one end the shaft has the drive pulley 67, said pulley having a pin 68 on the same side of the shaft as the cam 66, for an object presently to be described. The shaft 65 extends through, and is journaled in all of the frames 4 to 7 inclusive. 110

At the top of each of the frame members there is a shaft 69, which shaft has a suitable crank arm 70 for its operation by the lever 71, extending by suitable linkage 72 into a convenient place for the player to 115 operate.

This shaft is provided with a plurality of arms 73, so that by turning the shaft the continuous tone hammers can be held closer to the strings than they are to diminish the blow which they will strike. 120

The arms 73 are each provided with a small felt roller 73' for pushing the hammer 64 toward the strings with the least friction, and the player softens the effect of 125 130

the small hammers by pushing the link 72, which is connected to the lever 70, extending from one of the arms 73.

It is well understood by those skilled in the art that the location of the several levers is intended to be merely diagrammatic for the purpose of illustration, their actual location and the precise linkage for a finished instrument being variable at will and forming per se no part of the present invention.

It will be seen that when the key 2 is struck that the hammer is thrown up so the head 52 strikes the spring 54, said spring being supported from the rail 10 by a small block 54', secured thereunder. This spring is for the purpose of quickly pushing the hammer back with the head 52, and stop 51 in contact, but it is also necessary to pull the hammer 37 back quickly and to pull the small hammer 64 down on the damper 36.

These latter results are accomplished by the rod 80 which has a slot through which the screw 81 passes for the adjustment of the rod 80 with respect to the shank of the hammer.

This result is attained by loosening the screw 81, and moving the rod 80 until it strikes the rod 46 at just the correct instant, and to lift the shank 60 to bring the shank 62 into contact with the cam 66.

Examining now, Figs. 1 to 4, it will be seen that the lever 90 is arranged to hold the cam in either the up or down position when stopped, said lever being operated by the pin 68 on a slideable block 91.

The block 91 is slideable over the rod 92 connected to the block 93 and to the case of the motor "M". The slideable block enables the friction wheel 94 to be slideably moved along the shaft 96 and across the face of the friction disk 95 whereby the cam may be driven, at any desired speed.

Now it will be seen that in the event that the electric motor be started that the disk 95 will push the wheel 94 from a low speed position to a high speed position and at the same time the lever 90 will be disengaged from the wheel pin 68, to allow the cam to rotate. A link 96' and lever 97 afford means for the player to operate the cam 66 at any desired speed and the rod 72 allows the necessary adjustment of blow.

The back end of the rod 80 is shaped like the letter U turned sidewise, and embraces the rod 60, so that when the steady rest 51 advances it will lift the small hammer 64 and at the same time bring its spring shank closer to the cam 66.

At the back of the rail 9, there is the loud pedal rod 100, common to many actions.

The motor "M" rests on a bracket 101, secured inside the frame 1, and the large

friction pulley 95 drives the small pulley 67 by the belt 102.

It will also be seen that the top of the lever 90 is V-shaped to insure pushing the pin 68 up or down when the motor is stopped, this being necessary because of the small space in which the cam 66 must operate.

The playing of the piano is precisely the same as the playing of any other piano, and if the notes are short there will be practically no audible difference in the music produced, but whenever there is a sustained note the tone of the note will be actually sustained throughout the entire period desired, because the hammer 64 will be striking the string at a rate so fast that the ear cannot detect the separate blows, and because the damper is also lifted off the string at this same time.

If a chord is struck the tone of the chord will continue as long as the keys are held depressed, and the loudness of the tone will be regulated by the rod 72.

It will also be seen that the part of the rod 80, at 80', embracing the rod 60, extends into the path of the hammer shank 46, and serves as the common slack motion bridle straps do to pull the hammer back quickly. This also does away with lost motion between the jack and hammer butt when the soft pedal is used.

In the form of the invention shown in Figs. 7 and 8, the continuous tone hammer operating mechanism is shown as independent of the standard piano hammer action as shown in Figs. 1 to 6 inclusive, and forms a complete musical instrument in itself, on which a wide variation of tones can be obtained by adjustments and modifications.

This action is very simple and consists of the frame 105 of which there are usually four in an instrument, mounted on the frames are the rails 106, 107, 108. The rail 106 has fixed thereon the block 109 in which is pivoted the butt 110 to which the continuous tone hammer shank 111 is attached, and on the upturned end of which a butt 112 is fixed.

The flexible spring shank is shown at 113, the felt hammer 114, and felt pad 115.

The string is shown at 116, the damper 117 and damper rod 118, adjustably fixed to the damper lever 119 by the clamp bolt 120.

The damper lever is pivoted on the block 121, secured on the rail 107. The damper pad is indicated at 122, the wippen at 123 is pivoted on the block 124 which is secured to the rail 107.

In this instance the damper spoon 125 is adjustably held by means of a screw 126 in a longitudinal hole through the wippen. The wippen is operated as usual by means of the key 127, the abstract 128, guide link 129,

129 pivoted to the block 130, and 131 is the adjusting capstan.

The wippen 123 is connected to the hammer 111 by means of the wire rod 132, which has both ends threaded, one being screwed into a block pivoted on the wippen and the other end being clamped into a U-shaped loop in the shank 111 by means of the wooden nuts 133 and 134, lined with felt 135 and 136.

The cam is shown at 137, mounted on the rod 138, which has bearings in the frames 105, and has the pulley wheel 139 which is adapted to be driven by an electric motor, or other power means, in the same manner as described for the Figs. 1 to 6 inclusive.

To soften the effect of the hammer 114, a rod 140 is provided, mounted to swing in on the pivots 141, by means of the links 142, a collar 143 with a rod handle 144 is provided for pushing the rod 140 on the felt pad 115 of the hammer.

The operation of this action is as follows:

When the key is pressed down the rod 132 is raised, and with it the shank 111 carrying the hammer 114, up within range of the cam 137 which is revolving at a predetermined speed, or at a speed that can be varied at will.

By pushing on the handle 144, the rod 140 comes in contact with the felt pad on the hammer shank and causes the hammer to make shorter strokes, and thus the tone can be softened at will.

What I claim is as follows, but various modifications may be made in the construction shown in the drawings and above particularly described form, within the purview of my invention.

1. In a piano action, a key, wippen, damper lever, hammer and means connecting them for the usual playing operation,

and a damper spoon adapted to be moved to bear upon a damper lever, said spoon being bent substantially at a right angle 45 adjacent the damper lever, and bent substantially 180° at its opposite end, to be slidable into a hole in the front end of the wippen, whereby it may be adjusted to the proper position with respect to the damper 50 from the front of the piano, and without removing the wippen therefrom.

2. A stringed instrument of the class described comprising a piano string, a hammer mounted on a butt by means of a spring 55 and action, a revoluble cam, a shank connecting said butt with a pivot block, a wippen operated by the piano action, an adjustable rod connecting said wippen with said hammer shank whereby said hammer 60 may be raised within striking distance of said strings and within the path of the cam, said cam being adapted to throw said hammer against said string and power means for operating said cam.

3. A stringed instrument of the class described comprising two or more vertical frames on which are mounted transverse horizontal rails in parallel and spaced relation one above another, a hammer shank 70 pivoted to the upper of said rails, said shank being upturned and carrying a butt, a flexible spring extending upward from said butt, a felt hammer on said spring, a felt lining for said spring and butt, a motor driven cam adapted to strike said flexible spring and cause said hammer to strike a piano string when said hammer shank is raised, means to raise said shank by striking a piano key and means to regulate 75 the strokes of said hammer.

In testimony whereof I have hereunto set my hand this 19th day of June, A. D. 1925.

JAMES F. VEACO.
